MAXWELL MAYHEW UPSON, OF ENGLEWOOD, NEW JERSEY.

ERECTING FOUNDATIONS UNDER WATER.

Application filed May 15, 1925. Serial No. 30,476.

It has long been known that concrete structures erected in salt water are sometimes subject to attack thereby, and this fact has militated against the use of concrete in such locations. In the course of an extended experience with concrete structures in salt water I have observed that the attack occurs chiefly between high and low water levels, and believing that this was due largely to alternate submersion in the water and exposure to the air during the setting of the concrete I adopted the plan of using only precast concrete in situations where such alternate exposure and submersion is encountered. The precast units, thoroughly set and cured before sinking, were found to be resistant to sea water attack, and hence demonstrated that concrete in salt water could be made permanent and satisfactory.

The method referred to is simple, and has become standard practice where the loads to be carried by the structure are not too heavy, so that the units or elements employed can be small enough to be handled economically and sunk by driving or jetting, but where heavy loads are to be supported, as in the case of large piers and abutments, or large building foundations, the problem becomes more complicated. I have therefore been led to devise my present invention, which has for its chief object to provide a simple and economical method by which concrete structures can be erected in tidewater or other locations under water, without subjecting any part of the structure to alternate submersion and exposure during setting. To this and other ends the invention comprises the novel features of method and apparatus and combinations of steps and elements hereinafter described.

The invention is especially advantageous in erecting columns or piers on piling, and accordingly the preferred way of carrying out the invention will be described as employed for that purpose, using as an example the erection of a pier or column for supporting a bridge.

In carrying out the invention in the preferred manner for the purpose just indicated, the piles are preferably arranged in groups and may be wood or concrete, but I prefer the latter. They are driven far enough to bring their butts well below the surface of low water and still leave their tops a substantial distance above the ground. Around the submerged upper ends of the

piles I place a shell of steel or other suitable material, open at top and bottom but extending well above the water at high tide. The shell is supported in any convenient manner, usually by allowing its lower edge to rest on the ground, taking such precautions as may be necessary or desirable to prevent the shell from sinking too far into the ground. A layer of sand or other suitable material is now placed on the ground around the piles, inside of the shell, followed by a layer of tremie concrete, which is allowed to set. This concrete layer, in close contact with the piles and the inner surface of the shell, acts as a seal, so that the water in the shell can be pumped out, leaving a dry chamber in which the remaining portion of the work can be carried out. The firm adhesion of the concrete seal to the piles effectively resists the uplift of the outside water after the shell is emptied.

Referring now to the drawings,

Fig. 1 is a side view of a group of piles, under water.

Fig. 2 is a side view of the same group, with the shell and layers of sand and concrete in section, after the water is pumped out of the shell.

Fig. 3 is a plan view of Fig. 2.

Fig. 4 is a side view, partly in section, of a later stage of the work.

Fig. 5 is a plan view of Fig. 4.

Fig. 6 is a side view of the complete pier, with part of the superstructure.

The piles 10 are preferably precast concrete, and are provided with suitable reinforcing members, as 11, extending well above the tops of the piles. The group shown consists of six piles, but more or less than six may be used, according to the load to be carried per pile, and in some cases a single pile may be sufficient. The piles are sunk in any convenient and suitable manner, and are left with their butts projecting above the bottom far enough to afford secure anchorage and support for the cap or footing which is to be cast upon them. The tops of the piles should be below low water, indicated on the drawings by the broken line marked M. L. T., these letters standing for "mean low tide".

The shell 12 may be of heavy sheet steel, and to facilitate removal later, it may have a slight upward taper, or it may be split longitudinally, as indicated at 13, the edges at this point being releasably locked to

gether by any convenient and suitable means, not shown. The shell may be of any desired cross-sectional shape, but its height should be sufficient to bring its open upper end above high water, indicated by the line M. H. T., these letters standing for "mean high tide".

The shell 12 having been arranged as in Fig. 2, a relatively thin layer 14 of suitable material, as sand or clay, is laid on the ground around the piles inside of the shell, and on the sand layer a layer of tremie concrete 15 is laid. The thickness of the sand layer is at least sufficient to afford adequate support to the tremie layer and locate the underside of the latter at the proper height above the ground, and the thickness of the tremie layer is sufficient to provide an adequate water-seal and firm adhesion to the piles 10, at the same time exposing the ends of the piles far enough to be securely embedded in the cap which is later cast on top of the same. Also, the layer 15 is low enough to be entirely submerged at low tide. When the layer has set, the water is pumped out of the shell, as in Fig. 2. It will be observed that the tremie layer is protected by the shell or casing from the wash of the tide or other currents and is thus kept substantially undisturbed during setting.

The remaining parts of the concrete pier can now be cast in place, inside of the shell 12, and can set "in the dry", but I prefer to use precast units as far as possible, and accordingly I suspend in the shell, from the top, a precast column or part of a column 16. A convenient method of supporting the column is to clamp the same firmly between timbers 17 by means of bolts 18 and rest the timbers on the top of the shell, as clearly shown in Figs. 4 and 5. This method permits easy shifting of the column horizontally to position it with respect to other columns or to bring it exactly to the proper position with respect to the superstructure which it is to support. The column 16 may be provided with suitable reinforcing members, as 19, preferably overlapping the members 11 of the piles 10 at the bottom of the column and extending out at the top far enough for secure anchorage in whatever concrete element or part is later cast on top.

I now cast a cap or body of concrete 20 in the shell as a mold, embedding the upper ends of the piles 10 and enough of the lower end of the column 16, as indicated in Fig. 4, to prevent the water from working its way into the steel 11, 19. As the concrete is deposited, additional reinforcement may be placed therein, as the horizontal members indicated in dotted lines at 21.

The cap or body 20, nowhere in contact with sea water, is left to set, after which the timbers 17 are removed, followed by the shell

12. Fig. 6 shows the completed pier used as a support for a superstructure 22.

Instead of removing the water from the casing after the sealing layer 15 has set, enough water may be left in it, or even added if necessary, to a height somewhat above the plane at which the top of the connecting cap or footing 20 is to be located. The cap can then be cast and allowed to set while entirely submerged, thus avoiding injury incident to repeated exposure and submersion while setting.

It will be seen that the pier is composed of an upper precast member (16), a lower precast member or group of members (10), and an intermediate connection (15-20) which constitutes a footing of approved design. The portion 20 is placed and set in the dry. The tremie concrete portion 15 is placed and set in the wet, but since it is not subjected to alternate exposure and submersion it is not later subject to injury by the salt water, but even if it should be, the structure would not be materially weakened since the cap 20 rests on the piles themselves and does not depend upon the tremie layer for support.

It is to be understood that the invention is not limited to the procedure or structure herein specifically illustrated and described but can be carried out in other ways without departure from its spirit. While the invention is especially useful for erecting foundations and other structures in tide-water it may be used to advantage in other situations where the structure will be partially or wholly submerged.

I claim—

1. In a method of erecting foundations, placing a lower supporting member in the ground under water, arranging an upper precast concrete member above the lower member, and while excluding the water from around the adjacent portions of said members, casting a connecting body of concrete between said members and allowing the connecting body to set.

2. In a method of erecting foundations, placing a lower supporting member in the ground under water, enclosing the upper portion of said lower member in a removable water-tight casing extending upwardly above the water and removing the water therefrom, arranging an upper precast concrete member in the dry chamber thus provided and above the lower member, casting a body of concrete between the upper and lower members to support the former on the latter and allowing the supporting body to set in the dry, and thereafter removing the casing.

3. In a method of erecting foundations, placing a precast concrete lower member in the ground under water, enclosing the upper portion of said lower member in a removable

- water-tight casing extending upwardly above the water and removing the water therefrom, arranging an upper precast member in the dry chamber thus provided and above the lower member, casting a connecting body of concrete between the upper and lower members and allowing the connecting body to set in the dry, and thereafter removing the casing. 65
- 5 10 4. In a method of erecting concrete foundations in tidewater, placing a precast lower member in the ground below low water, enclosing the upper portion of said lower member in a removable water-tight casing 70
- 15 extending upwardly above high water and removing the water therefrom, arranging in the dry chamber thus provided and above the lower member an upper precast concrete member extending above and below the surface plane of high water, casting a connecting body of concrete between the upper and lower members and allowing the connecting body to set in the dry, and thereafter removing the casing. 75
- 20 25 5. In a method of erecting foundations in tidewater, placing a lower precast concrete supporting member in the ground under low water, arranging an upright casing around the lower member, open at top and bottom and extending above high water, placing a layer of concrete in the lower part of the casing, in sealing contact with the said lower member and the inner surface of the casing, and allowing the concrete to set under water, 80
- 30 35 removing the water from the casing to provide a dry chamber, suspending a precast concrete member in the dry chamber from above, with its lower end adjacent to the said lower member, casting a connecting body of concrete between the said upper and lower members, and after the concrete has set, removing the casing. 85
- 40 45 6. In a method of erecting foundations, placing in the ground under water a lower precast concrete supporting member, arranging around the said lower member a removable water-tight casing and removing the water therefrom to provide a dry chamber, arranging in the latter a precast concrete upper member adjacent to said lower member, casting between said members a reinforced concrete connecting body and allowing the same to set, and thereafter removing the casing. 90
- 50 55 7. In a method of erecting foundations, placing in the ground under water a lower precast concrete supporting member having reinforcing members protruding from its upper end, arranging around the said lower member a removable water-tight casing and removing the water therefrom to provide a dry chamber, arranging in the latter a precast concrete upper member having rein- 95
- forcing members protruding from its lower end, casting between said upper and lower members a concrete body embedding the reinforcing members and connecting the said precast concrete members, allowing the concrete connecting body to set, and thereafter removing the said casing. 100
- 100 105 8. In a method of erecting foundations in tidewater, placing in the ground under low water a lower precast concrete supporting member, arranging around the said lower member a casing open at top and bottom and extending above high water, placing a layer of concrete in the lower part of the casing, in sealing contact with the said lower member and the casing, and allowing the concrete layer to set, removing the water from the casing to provide a dry chamber enclosing said lower member, suspending in the chamber a precast upper member with its lower end below high water level, casting between said upper and lower members a connecting body of concrete embedding the adjacent ends of said members, allowing said body to set, and thereafter removing said casing. 110
- 110 115 9. In a method of erecting foundations in tidewater, placing in the ground under low water a lower precast concrete supporting member, arranging around the said lower member a removable water-tight casing and removing the water therefrom to provide a dry chamber, suspending in the latter from its upper edge a precast upper member shiftable horizontally to bring it into predetermined position with respect to other portions of the work, casting a connecting body of concrete between said upper and lower members, allowing the concrete body to set, and thereafter removing said casing. 120
- 120 10. In a method of erecting foundations in tidewater, setting a group of precast concrete piles in the ground under low water, arranging around the group of piles a casing open at top and bottom and extending above high water, placing in the lower part of the casing below low water a layer of concrete in sealing contact with the piles and with the inner surface of the casing, allowing the concrete layer to set under water and removing the water from the casing to provide a dry chamber, arranging in the chamber an upper precast member with its lower end below and its upper end above high water, casting a body of concrete on the said concrete layer and embedding the adjacent tops of the piles and the lower end of the upper to provide a cap for the piles and a footing for said member, allowing the concrete body to set in the dry chamber, and thereafter removing the casing.

In testimony whereof I hereto affix my signature.

MAXWELL MAYHEW UPSON.
